Inventor

Robert R. Ball

UNITED STATES PATENT OFFICE.

ROBERT R. BALL, OF NEW YORK, N. Y.

LOCK.

SPECIFICATION forming part of Letters Patent No. 548,418, dated October 22, 1895.

Application filed May 28, 1894. Serial No. 512,818. (No model.)

To all whom it may concern:

Be it known that I, ROBERT R. BALL, a citizen of the United States, residing in the city of New York, county and State of New York, have 5 invented a new and useful Locking Device, of which the following is a specification.

My invention relates to improvements in locks, and has for its objects, first, to provide a simple, cheap, and effective tubular locking device, occupying small space, easy of application, and especially adapted to standard latches which are operated by a spindle; further, to construct a lock which is difficult to pick or operate without the proper key. I attain 15 these objects in the manner fully set forth in the accompanying drawings, which form a part of this application, and in which—

Figure 1 is a central vertical section of my novel lock as upon the line $\alpha\alpha$ of Fig. 3, and 20 shows in connection therewith a suitable form of latch. Fig. 2 is a similar vertical section, but showing a slightly-modified construction and adapted to a knob-handle. Fig. 3 is a face view of the escutcheon N. Fig. 4 is a 25 perspective view of the slidable interlocking piece employed in the construction illustrated in Fig. 2. Fig. 5 is a perspective view of the slidable interlocking piece illustrated in Fig. 1. Fig. 6 is a perspective view of the key-30 socket. Figs. 7 and 8 show the several parts of the key-socket disassembled. Fig. 9 is a 35 plan view of the tube or lock-case. Fig. 10 shows the key in elevation. Fig. 11 is an end elevation of Fig. 2.

Similar letters and numerals of reference 40 denote like or corresponding parts throughout the several views.

My novel lock can only be operated by a key which is especially fitted to the socket. 45 By the insertion of this key the several parts are operatively assembled.

Referring to the letters and numerals of reference, L indicates a suitable form of latch, which may be either a surface or mortise latch. 50 Said latch, as will be seen, is provided with a square hole, through which the rectangular spindle H of my lock is inserted. Upon the inner end of this spindle (see Fig. 1) I have secured a thumb-piece N'. The outer casing C 55 may be of the construction shown in either Figs. 1 or 2. It is of a cylindrical formation and serves to inclose the rotary tube A. The

interlocking parts of this device are contained within the tube, as will be clearly understood with reference to Figs. 1 and 2. The inner end 55 of this tube A is closed by means of a plug B, which is secured in position in any preferred manner. It may be pinned or screwed, as shown. This plug is provided with a central base w, through which the spindle H freely 60 passes. In Fig. 1 of the drawings I have shown a collar p, keyed to the spindle adjacent to the plug, which collar prevents the withdrawal of said spindle and insures its retention in the desired position. In Fig. 2 of 65 the drawings I show a pin p', which answers the same purpose and also serves in another capacity, as will be later referred to.

Within the rotary tube A is carried a movable locking-piece 3. This is clearly illustrated in Figs. 4 and 5. As shown, this piece is provided with grooves e e to receive the ways c c, stamped in at opposite sides from the tube, which prevent a rotary movement of the locking-piece independent of the tube 75 A. The outer end of this locking-piece is beveled, as indicated at b, for engagement of the points of the key. The other end of this locking-piece is provided with a central orifice f to receive the end of the spindle H. The orifice of one form of locking-piece, it will be seen, is square, while that of the other form is round. The same is true of the end of the spindle H, as shown, and said spindle is designed to fit into said orifice in the manner 80 illustrated against the resistance of a spiral spring i. This spring serves to force the locking-piece outward off from the spindle to insure its disengagement therewith at such times when the key is not inserted. 85

Referring to Figs. 2 and 4 it will be seen that the locking-piece is provided with recesses d, which serve to engage the pin p' at such times when said locking-piece is forced forward by the insertion of the key, and by 90 this connection the spindle and tube are operatively united and may be turned together. In Figs. 1 and 5 these two parts are operatively connected by means of the square orifice f engaging the square end of the spindle 95 i. against the action of the spring i.

Within the end of the tube A, I fit a specially-constructed key-socket 1. This socket is formed complete of three parts, to wit: the two

side plates and a disk 2, which disk accurately fits the inside of the tube A. These plates are each provided with spring-wards *g*, which are pressed or stamped in from the stock, one end being left free, thus affording said wards a slight yielding or spring action. In addition to these wards I provide additional obstructions in the form of nipples *g*². The location of these may be varied at will to accommodate the differences in the different keys. The disk 2, as shown, is connected to the plates by having slots designed to receive the points *k* of said plates, and whereby one end of the plates are firmly secured. The outer, upper, and lower corners are also provided with points *g*', which fit into slots *h* of the tube and which serve to retain the forward ends of the plates together, thus forming a complete key-socket from sheet metal in an efficient and inexpensive manner.

The key *K* is provided with ways *n* and *n*', which are fitted to the wards of the socket. The points *m* and *m* of the key are designed to freely pass between the plates and through the slots *o* of the disk and are for the purpose of engagement with the bevel portion 3 of the locking-piece.

When the key is inserted as above stated and it comes in contact with the locking-piece, the said key and locking-piece are forced home against the action of the before-mentioned spring *i*, thus uniting the locking-piece with the spindle and permitting of a rotary movement being imparted thereto.

Having thus described my invention, I claim—

1. In a locking device of the class described, the combination with a rotary cylindrical operating tube, of a flat key socket formed of sheet metal substantially as shown and provided with one or more spring wards for the frictional engagements for the ways of the key, for the purpose specified.

2. In a locking device of the class described the combination with a knob and a rectangular spindle, of a rotary tube interposed between said knob and spindle; a cylindrical movable locking piece having ways, *e*, upon its periphery to engage ways of the tube and the peripheral beveled end, *b*; means for interlocking the said locking piece with the spindle, and a spring for normally holding the said locking piece out of engagement with the spindle, all operatively assembled substantially as set forth. 55

3. In a locking device of the class described, the combination with a spindle, of a tube secured on the end thereof, a locking piece fitted in the said tube and movable upon said spindle provided with a peripheral beveled surface, a key socket in the end of the tube constructed with openings in the disk to permit of the points of the key extending through and engaging said bevel portion of the locking piece, means for uniting the locking piece to the spindle, substantially as set forth. 65

4. In locking mechanism of the class described the combination with a casing, of a cylindrical tube A, plug B, in the end thereof having a spindle journaled therein, a pin, *p*, supported in said spindle, a slideable locking piece fitted in said tube and having recesses, *d*, to engage the pin of the spindle by the introduction of a key, substantially as set forth. 70

5. In a locking device of the character described the combination of a cylindrical tube A, provided with ways *c*, *c*, the beveled interlocking piece 3, having ways *e*, a key socket formed of plates 1, and disk 2, the spindle H, spring *f*, all arranged and to be operated by a key substantially as set forth. 75
